UNITED STATES PATENT OFFICE.

WILLIAM A. BOCK AND RICHARD G. BOCK, OF CHICAGO, ILLINOIS.

CAR-DOOR-OPERATING DEVICE.

1,299,420.

Specification of Letters Patent.

Patented Apr. 8, 1919.

Application filed March 25, 1918. Serial No. 224,552.

To all whom it may concern:

Be it known that we, WILLIAM A. BOCK and RICHARD G. BOCK, both citizens of the United States, residing at Chicago, Cook county, Illinois, have invented a certain new and useful Improvement in Car-Door-Operating Devices, of which the following is a full, clear, concise, and exact description, reference being had to the accompanying drawings, forming a part of this specification.

This invention relates to improvements in car door operating devices.

As is well known, great difficulty has heretofore been encountered in the opening and closing of the side doors of railway freight cars which results from the sagging of the cars themselves; sagging of the doors; injury to the door supporting tracks and brackets; and oftentimes due to the fact that some of the load of the car has shifted against the doors while the cars are in transit. Heretofore, so far as we are aware, the only method of forcing the doors open or of closing them when the difficulties above mentioned have been encountered has been to employ some improvised means, generally a crow-bar or piece of joist, to pry the doors, and thereby causing serious damage to the cars and doors, and in addition, requiring an unnecessary expenditure of time and labor.

One object of our invention is to provide a simple and efficient device which may be readily applied to a freight car and employed to force the door either open or closed and without danger of injuring the car or door.

Another object of our invention is to provide a device of the character above indicated which may be detachably applied to any portion of any of the usual types of door hanger tracks now used so that the device may be employed to move the door regardless of the position of the latter.

Another and more specific object of our invention is to provide a door operating device of the character above indicated which may be employed without modification for forcing the doors either open or closed, that is, a device so arranged that it can be operated either right or left.

In the drawing forming a part of this specification, Figure 1 is a side elevational view of a portion of a box freight car showing the side door opening thereof and a section of the side door in partly opened

position, our improved operating device being shown in position to force the door still farther open. Fig. 2 is a vertical, transverse, sectional view, taken substantially on the line 2-2 of Fig. 1. And Fig. 3 is an elevational view showing the manner of attaching our device to a different form of door hanger track from that shown in Figs. 1 and 2.

In said drawing, 10 denotes a freight car of the box type having the usual side door opening above which extends horizontally a Z-bar door hanger track 11 of well known form, the same being secured to the upper portion of the car side wall in the usual manner. The side door of the car is designated at 12, the same being supported from the track 11 by any suitable means, such as the roller hanger brackets 13.

To open and close the door when unusual force is required, we employ the device designated generally by the reference A. Said device, as shown, includes three elements 14, 15 and 116. The member 15 may be called the supporting member and is formed at its upper end with a horizontally extending flange or lip 16 adapted to rest on the horizontal web of the track 11. Below the horizontal flange 16, the member 15 is extended downwardly for a relatively short distance and is then carried outwardly, as indicated at 17 to thereby form an offset 18 for the purpose hereinafter described. At its lower end, the member 15 has pivoted thereto the operating lever or member 14, the pivot being preferably in the form of a rivet 19. The lever 14 at its upper end is forked, as indicated at 20, and between the forks is mounted a loosely rotatable anti-friction roller 21 having its periphery preferably concaved, as indicated at 22, and adapted to engage the edge of the car door. Below the pivot 19, the lever 14 is preferably offset, as indicated at 23, so as to provide greater clearance when the same is being operated.

In order to clamp the device in fixed position on the door hanger track, we employ the gravity actuated cam lock 116 which is pivotally attached to the supporting member 15 as by the rivet 24. Said member 116 at its upper end is provided with a curved cam surface, as indicated at 25, so spaced with relation to the flange 16 that the rail track, when the latter has a horizontal section, as indicated in Fig. 2, will be securely gripped therebetween. At its lower end, the mem-

ber 116 is enlarged, as indicated at 26, so that it is weighted in such a manner as to tend to throw the member 116 to a vertical position and parallel with the supporting 5 member 15.

When the device is employed on a car having a so-called plate or bar hanger track, as indicated at 27 in Fig. 3, it is necessary to employ a different gripping arrangement 10 and for this purpose the member 116 is provided with another cam surface 28 so spaced with relation to the horizontal flange 16 that the rail or track 27 will be gripped therebetween. It will be noted that the member 15 has the upper portion thereof which carries the cam surface 25, relatively narrow and spaced from the member 15 sufficiently to admit the depending flange of a Z-bar track therebetween and to form sufficient 20 clearance for a track of the type shown in Fig. 3.

In attaching the device to a door track, it is desirable to prevent the members 15 and 116 from swinging relatively to the operating lever 14, the latter being, of course used by the operator when the device is being lifted into position. To accomplish this result, the lever 14 is provided with an elongated slot 29 where the pivot 19 is accommodated so that the lever 14 and supporting member 15 are shiftable relatively longitudinally. In the offset 18 of the member 15, we provide a small lug 30 which is adapted to be seated in a corresponding 35 notch 31 formed in the upper end of the adjacent fork 20 of the lever 14. By referring to Fig. 3, it will be seen that when the lever 14 is shifted upwardly relatively to the member 15, the notch and lug 30 will 40 be engaged which will therefore prevent the member 15 from swinging while it is being applied. When the lever is being actuated to open the door, however, it is obvious that it will be drawn down so as to be disengaged 45 from the lug 30.

In case it should be found necessary to positively position the cam locking member 116, the latter may be provided with an opening 32 to receive the bent upper end of 50 a suitable rod or the like which can be manipulated by the operator when standing on the ground.

The lower end of the operating lever 14 is preferably made wedge-shape, as indicated 55 at 33, so that it can be utilized in the manner of a pinch bar.

With the parts in the position shown in Fig. 1 and the operator swinging the lower end of the lever 14 to the left, as viewed in 60 said figure, it is evident that there will be a tendency to shift the pivot 19 to the left and consequently the pivot 24 in a similar direction. This will force the cam locking element 116 into tight gripping engagement 65 with the track 11 and positively prevent the

device from shifting accidentally lengthwise of the track, although it is evident that the device can be shifted along the track to the right, as the door is progressively forced open, without difficulty or without disengaging the device from the track. 70

When it is desired to use the device for forcing the door to closed position, it is merely necessary to swing cam locking member 116 to the other side of the vertical and 75 swing the operating lever 14 in the opposite manner to that shown in Fig. 1.

The device can obviously be manufactured at relatively small expense, can be used with cars employing different types of door 80 hanger tracks and will successfully and efficiently serve the purpose intended and without danger of injury to the car or door.

We claim:

1. A door operating device for car doors 85 and the like including, in combination: a member adapted to be supported in a depending position from a door hanger track of a type having either a horizontal or vertical supporting section; door engaging 90 means movably supported from said member; and means mounted on and co-acting with said member adapted to grip either of said types of track when the device is applied thereto. 95

2. A door operating device for car doors and the like including, in combination: a member adapted to be supported from a door hanger track; adjustable means associated therewith for detachably but fixedly gripping the track; to prevent movement of said member in either direction depending upon the adjustment of said means; and a door engaging lever operable in either direction to force the door either closed or open. 105

3. A door operating device for doors supported from a hanger track including, in combination: a member adapted to be supported in a depending position from the hanger track; a gravity controlled cam locking element co-operable with and pivotally mounted on said member adapted to automatically grip the track; and a second member movably mounted on the first named member and adapted to engage the door to 115 shift the same lengthwise of the track. 110

4. A door operating device for slidable car doors and the like including, in combination: two pivotally connected elements having co-operating means for engaging and 120 gripping a door hanger track therebetween; and a door engaging lever pivotally mounted intermediate its ends on one of said members, said lever being pivoted to swing to either side of the member to which it is pivoted to thereby adapt the same for forcing the door in either direction. 125

5. A door operating device of the character described including, in combination: a supporting member having an offset flange 130

adapted to engage the top of a door hanger rail of either a Z-bar or plate type; a gravity controlled, pivoted cam locking element mounted on said member, said locking element having two cam faces located at different distances from said flange and co-operable with the latter to grip either of said types of hanger tracks; and a lever pivotally mounted on said member and adapted 10 to engage one edge of a door supported from said track and force the latter lengthwise of the track.

6. In a door operating device for car doors and the like, the combination with a hanger 15 having an inturned flange at its upper end by which said hanger is adapted to be supported from a door hanger track, of a lever pivotally attached to said hanger, said lever being adapted to swing to either side 20 of said hanger to engage the edge of a door, of a gravity cam locking element also pivotally attached to said hanger adjacent said flange, said cam locking element having a

plurality of gripping surfaces opposed to and co-operable with said flange to thereby 25 clamp the mechanism to the door hanger track, said gripping surfaces being disposed at different distances from said flange.

7. In a door operating device of the character described, the combination with a supporting member adapted to engage with a door hanger track, of means co-operable with said member adapted to grip a track, an operating lever pivotally attached to said member, said lever being adjustable lengthwise of 30 said member in addition to its pivotal attachment, and co-operating means on said member and lever adapted to engage when said lever is shifted with respect to said member to thereby lock said lever and member together and facilitate application of the device to a track.

In witness that we claim the foregoing we have hereunto subscribed our names.

WILLIAM A. BOCK.
RICHARD G. BOCK.
